LENS RIM

Frank W. Lindblom, Auburn, R. I., assignor to
Welsh Manufacturing Company, a corporation
of Rhode Island

Application February 27, 1941, Serial No. 380,828

1 Claim. (Cl. 88—47)

This invention relates to an ophthalmic mounting, particularly the rim thereof.

Heretofore in the use of lens rims for an inexpensive securing of the rim about the lens, it has been usual to provide a box on one end of the rim to slide along a bridge connection to close the rim on the lens. Lenses differ in size to such an extent that it is difficult to have a meeting of the ends at the joint of the rim, and unless these portions abut, they are unsightly.

One of the objects of this invention is to provide an arrangement whereby some variation in the size of the lens rim may be had and yet an unsightly joint will be eliminated in a very inexpensive manner.

With this and other objects in view, the invention consists of certain novel features of construction, as will be more fully described, and particularly pointed out in the appended claim.

In the accompanying drawing:

Fig. 1 is a face view of a frame with lenses mounted therein;

Fig. 2 is a central section through the rim and lens illustrating the joint in secured position;

Fig. 3 is a section on line 3—3 of Fig. 2;

Figs. 4 and 5 are oppositely arranged perspective views of the rim prior to embracing the lens; and

Fig. 6 is a perspective view similar to Fig. 5, but showing a modified arrangement of the rim.

In carrying out this invention, I have found a simple manner of connecting the rim end portions about the lens by providing an opening on one end of the rim and a tongue on the other end to extend through this opening to be bent to hold the rim in desired position.

With reference to the drawing, 10 designates the body portion of a lens rim which is grooved as at 11 to receive the beveled edge 12 of the lens 13. One end of this channel-shaped rim is fashioned to provide a tongue 14 by cutting down the end portion, while the other end is provided with a shoe 15 which is of channel construction of a size to receive the end 16 of the body 10 and is secured thereto in any suitable manner such, for instance, as by welding or soldering. This

shoe is provided with an opening 17 of a size to receive the tongue 14, the arrangement being such that the end portion 18 of the body may also be received within the channel of shoe 15.

In this manner the channel will cover the joint formed between the ends of the shoe, and by the provision of a tongue sufficiently long, considerable variety of different sized lenses may be accommodated by merely passing the tongue through the opening 17 and bending the same over as at 19 (see Fig. 2).

The two lens rims in secured position are shown at 20 in Fig. 1 and are connected together by a bridge 21 held in boxes at its ends 22 in any suitable manner, which boxes are also secured to the rims.

Fingers 23 may be provided for holding the frame onto other ophthalmic mountings, which is effected by the springing together of the lens mountings through the action of the bridge 21.

In the showing in Fig. 6, I have illustrated that the rim may be ornamented as at 24 and have provided an opening 25 in the end of the body portion of the rim itself rather than in a separate shoe attached to the rim. The reduction of the tongue 14 is such that it may pass into the channel of the rim and extend through the opening 25 and be bent over as at 19.

In all cases, the tongue affords a complete closing of the joint of the lens rim; and in the use of the shoe, the side walls as well serve to close the joint between the ends of the rim in various positions of expansion.

I claim:

35. In an ophthalmic mounting, a lens rim having a body portion to encircle the lens, a shoe having an opening therein receiving the end of the body and attached thereto and extending from said body portion and with the opening located in the 40 extending part of said shoe, the other end of said body also being received in the extending part of said shoe and provided with a bendable tongue to extend through said opening and be bent to lock the ends of the rim in said shoe.

FRANK W. LINDBLOM.
